RADIO TRANSMITTER

Application filed May 19, 1927. Serial No. 192,520.

This invention has to do with vacuum tube signaling systems—especially high frequency transmitters—and relates more particularly to the conservation of the electrical energy supplied to vacuum tubes.

The specific embodiment of the invention described herein is a vacuum tube transmitter comprising a master-oscillator and power-amplifier, the former functioning to generate high frequency oscillations which may be of relatively small intensity and the latter functioning to amplify the oscillations produced by the master-oscillator before they are impressed upon the transmitting antenna.

The circuit arrangement to be described provides for complete and practically instantaneous stoppage of plate current both in the master-oscillator and power-amplifier except when signals are actually being transmitted, thereby effecting a large saving in current consumption. This is accomplished in a manner which is not only highly satisfactory from an operating standpoint, but one which results in simplicity of arrangement and an important saving of batteries—the size of batteries required being reduced to a minimum.

The principal feature of the invention as incorporated in the specific embodiment herein described, lies in a novel circuit arrangement whereby a high negative potential is normally applied to the grid of the power-amplifier tube, this potential being sufficient to completely stop the flow of plate-filament current in that tube, and being supplied, in part, by the battery which furnishes plate current to the master-oscillator. This double use of one battery results in a very substantial saving in operating cost.

The accompanying drawing illustrates diagrammatically the vacuum tube transmitter comprising a high frequency vacuum tube master-oscillator, designed to generate sustained oscillations and a vacuum tube power-amplifier which functions to amplify the oscillations generated by the master-oscillator and to impress the amplified oscillations upon a transmitting antenna. This general type of vacuum tube transmitter is widely used and has the important advantage that its out-

put frequency will remain substantially constant in spite of certain external disturbances such as swaying of the transmitting antenna and the like. This is due to the fact that the power-amplifier tube is unilaterally conductive and will not transmit to the master-oscillator disturbances which may occur in the antenna system. On short wave work this is a very important consideration and particularly so in portable installations wherein the antenna constants are apt to fluctuate to a considerable extent. 55

In the diagram, the master-oscillator portion of the system is shown below the dot-dash line X—X, while the power-amplifier and transmitting antenna are shown above that line. 60

The master-oscillator vacuum tube is indicated by reference numeral 1; the power-amplifier vacuum tube by reference numeral 2. 70

Vacuum tube 1 comprises a grid or control electrode 8, a plate 9 and a filament 10. The oscillator circuit is an adaptation of that described and claimed in United States Letters Patent, No. 1,585,244, granted to William H. Hoffman, May 18th, 1926, and is designed with a view particularly to efficient short wave transmission although its utility is not limited in that respect. The oscillator circuit comprises a pair of inductance coils 5 and 6 which preferably are of substantially equal inductance, and four condensers 7, 13, 14 and 17. The latter is indicated as being variable and in combination with condensers 13 and 14 functions as a frequency determining capacity. Condenser 7 is a stopping condenser which functions to permit the passage of high frequency currents while preventing the flow of direct current. A high resistance 15 is connected at one of its terminals to a point 16 between condenser 7 and inductance coil 6 while the other terminal of the resistance 15 is connected to a point between condensers 13 and 14. Condenser 7, being of relatively large capacity, offers substantially no impedance to the high frequency current, and accordingly the high frequency potential at point 16 is substantially the same as if that condenser were not present. The condensers 85

13 and 14 are preferably of equal capacity and for that reason the high frequency potential at their juncture is equal or substantially equal to that at point 16. That being the case, 5 there is substantially no high frequency current flow through resistance 15. The latter resistance functions as a leakage path between grid and filament and its value may be of the order of 5000 to 20,000 ohms.

10 The extremities of coils 5 and 6 are connected respectively to plate 9 and grid 8.

Plate current to the oscillator tube is supplied by a battery 24, the positive terminal of which is connected to the juncture between 15 coil 5 and condenser 7, the high frequency potential of which point is substantially equal to that of point 12 to which the filament is connected. The negative pole of battery 24 is connected to terminal 26, from which the circuit extends to negative filament through a 20 telegraph key or relay, the contact of which is normally open. From an examination of the diagram it will be seen that the high frequency current cannot flow to any substantial 25 extent from plate to filament through battery 24 because of the fact that the latter is connected across points of substantially equal high frequency potential.

The filaments of both vacuum tubes are 30 connected in parallel and supplied with heating current from a battery 18, or other suitable source of current which also may be alternating in character.

High frequency oscillatory exciting voltage 35 generated by the master-oscillator is supplied to the grid 19 of the power-amplifier tube through conductor 20 and stopping condenser 21. The connection of conductor 20 to coil 6 is indicated as being variable. This 40 permits an optimum value of exciting voltage being supplied to the power-amplifier tube.

The output or plate circuit of the power-amplifier tube includes a source of current such as a plate battery 28, a parallel tuned 45 circuit 29, 30 and an adjustable contact 31 by means of which a variable number of turns of the coil 29 may be connected between the battery 28 and plate 23. Tuning of the power-amplifier plate circuit is effected by means of 50 variable condenser 30. A source of alternating current also may be substituted for plate battery 28.

For the purpose of preventing the power-amplifier from oscillating independently of 55 the master-oscillator due to the internal grid-plate capacity of the power-amplifier tube, a small variable neutralizing condenser 22 is provided. This is connected between plate 23 and coil 5 and serves to impress on plate 60 23 a fluctuating potential which is equal and opposite to that caused by the internal tube capacity.

The transmitting antenna is indicated by 65 reference numeral 4 and includes a coil 3 which is inductively coupled with coil 29.

The high frequency energy to be radiated is thus impressed upon the antenna.

Where any substantial amount of energy is to be radiated the plate battery 28 is necessarily of considerable size and correspondingly expensive. Therefore, it is very desirable, if not entirely essential, to avoid any useless or unnecessary drain on that battery.

Likewise battery 24, though not usually as large as battery 28, is nevertheless generally 75 of substantial size and economy in its use is important.

Therefore, it is desirable to so arrange the circuit that when signals are not actually being sent out, there is no drain on the batteries referred to. To accomplish this end in a way which is both simple and satisfactory, the circuit is so arranged that a high negative potential is normally impressed on grid 19, this potential being sufficient to completely stop the flow of plate current in the power-amplifier tube, and the plate-filament circuit of the master-oscillator tube is at the same time held open.

A novel and outstanding feature of the arrangement lies in the utilization of master-oscillator plate battery 24 as a source of grid biasing potential for the power-amplifier tube and the arrangement of the keying device or starting relay contact so that upon closure the negative potential on the grid of the power-amplifier tube is reduced to the proper value for operation of that tube and at the same time the master-oscillator plate circuit is closed.

Assuming the key connected across terminals 26 and 27 to be open, batteries 24 and 25 are connected in series between plate 9 of the master-oscillator tube and grid 19 of the power-amplifier tube. It will be noted that with the key open there is no direct current connection from batteries 24 and 25 to filament, but, nevertheless, there is an effective negative potential impressed on grid 19, of sufficient intensity to completely or substantially stop the flow of plate current through the amplifier tube. This is believed to be due to the charging up of the internal grid-filament capacity of the amplifier tube—this capacity being in series with the batteries 24 and 25. The result is that when the key is 115 suddenly opened the grid 19 becomes highly negative with respect to filament.

Battery 24 is selected to give the proper plate voltage for the master-oscillator tube while battery 25 is selected with a view to 120 providing the desired negative bias on grid 19 when the power-amplifier is in operation. At the same time the combined voltages of those two batteries should be sufficient to provide the necessary negative potential on grid 19 to stop the flow of current from current source 28 when the key is opened.

Upon the closure of the telegraph key or relay contact across terminals 26 and 27, the negative terminal of battery 24 and the posi- 125

tive terminal of grid biasing battery 25 are connected simultaneously to the negative filament terminal and the circuit is thereupon put into operation. The plate circuit of the master-oscillator being completed oscillations are generated and the negative bias on grid 19 being lowered to the operating value, plate current flows in the power-amplifier tube. The response to the opening and closing of the key is without any apparent lag.

10 A radio frequency choke coil 32 is inserted in series with battery 25 to prevent passage of high frequency current therethrough.

By way of example, a radio telegraph transmitter exactly in accordance with the circuit 15 herein described has been constructed and successfully operated. The master-oscillator tube corresponding to tube 1 was of the receiving type commonly known by the designation UX-201-A.

The power amplifier was a 7½ watt tube (UX-210). Batteries 24, 25 and 28 were all dry cell batteries, battery 24 being of 180 20 volts, battery 25 of 22½ volts, battery 28 of 25 500 volts. Condenser 21 had a capacity of approximately 0.0001 microfarads, condenser 7 of 0.005 microfarads, condenser 13 of 0.0005 microfarads, condenser 14 of 0.0005 microfarads and condenser 17 had a maximum capacity of approximately 0.00005. The resistance element 15 had a value of approximately 20,000 ohms. The capacitance of condenser 22 was about 0.00005 microfarads maximum. Coils 5 and 6 each were 27/8" diameter and consisted of 5 turns of 12 gage copper wire. Coil 29 was 27/8" diameter and consisted of approximately 7 turns of 12 gage copper wire. Coil 3 was 21/2" diameter and consisted of 6 turns of 12 gage copper wire. 40 Choke coil 32 was 1½" in diameter and consisted of approximately 200 turns of 28 gage copper wire. The maximum capacity of variable condenser 30 was about 0.00025 microfarads.

45 While this invention has been described only in its application to one particular type of transmitter, it will be evident that it may be applied with equal advantage to vacuum tube systems of other forms and to wire transmission systems as well as radio. Also it will be recognized that the application of this invention may be made with equal facility to either radio telegraphy or telephony.

What is claimed is:

- 50 1. In a vacuum tube transmitter, a master-oscillator comprising a vacuum tube, a plate-filament circuit for said vacuum tube, a plate battery and circuit interrupting means in said plate-filament circuit, an amplifier comprising a vacuum tube, circuit connections between said master-oscillator and amplifier for supplying high frequency exciting voltage to the latter, a plate circuit for said amplifier including a second source of plate current, a grid circuit for said amplifier in- cluding a grid biasing battery, the negative terminal of which is connected to the grid of said amplifier tube, said first mentioned plate battery and said grid biasing battery being connected in series, a circuit connection between the positive terminal of said grid biasing battery and the filament of at least one of said vacuum tubes and circuit interrupting means in said last mentioned circuit connection.
- 55 2. A high frequency transmitting system comprising a vacuum tube master-oscillator and a vacuum tube power-amplifier, said master-oscillator being connected to the input terminals of said power-amplifier and functioning to supply exciting voltage thereto, said master-oscillator and power-amplifier each comprising a vacuum tube including a plate, a grid and a filament, two current sources connected in series the positive terminal of one of said current sources being connected to the plate of said master-oscillator tube and the negative terminal of the other of said sources being connected to the grid of said power-amplifier tube, the joint terminal between said current sources being adapted to be connected to a filament terminal of one of said tubes and means for interruptedly connecting said joint terminal to said filament terminal, the combined voltage of said current sources being such as to impress a sufficient negative bias on the grid of said power-amplifier tube substantially to prevent the flow of plate current through said tube.
- 60 3. In a high frequency wave signaling system a vacuum tube oscillator, a power-amplifier comprising a vacuum tube, said power-amplifier being operatively connected to said oscillator and adapted to amplify the oscillations produced by said oscillator, a source of unidirectional current connected between the plate and filament of said power-amplifier for supplying space current thereto, a current source connected between the grid of said power-amplifier and the plate of said oscillator whereby a negative potential is applied to the grid of said amplifier sufficient substantially to prevent any flow of current between the plate and filament of said power-amplifier, a part of the last mentioned current source being adapted to supply plate current to said oscillator, and switching means included in a direct-current circuit between the plate and filament of said oscillator, said last mentioned circuit including a part only of the current source between the plate of said oscillator and the grid of said power-amplifier, said switching means being operative to reduce the negative potential on the grid of said power-amplifier and at the same time to close the plate circuit of said oscillator thereby causing said oscillator to generate high frequency oscillations and

simultaneously rendering said power-amplifier operative to amplify said oscillations.

4. The method of operating a vacuum tube high frequency transmitter comprising a vacuum tube master-oscillator and a vacuum tube power-amplifier which consists in normally applying a negative potential to the grid of said power-amplifier of such value as substantially to stop the flow of plate current through said amplifier, reducing the negative bias on the grid of said power-amplifier sufficiently to permit a flow of plate current therethrough and simultaneously closing the plate circuit of said master-oscillator.

15 In testimony whereof I affix my signature.
